UNITED STATES PATENT OFFICE.

EDWIN L. YEWELL, OF WASHINGTON, DISTRICT OF COLUMBIA, ASSIGNOR
TO D. SLOTE & CO., OF NEW YORK, N. Y.

ATTACHMENT TO BOOKS.

SPECIFICATION forming part of Letters Patent No. 308,942, dated December 9, 1884.

Application filed November 12, 1883. (No model.)

To all whom it may concern:

Be it known that I, EDWIN L. YEWELL, a citizen of the United States, residing at Washington, in the District of Columbia, have invented certain new and useful Improvements 5 in Attachments to Books, of which the following is a specification, reference being had therein to the accompanying drawings.

This invention relates to certain improvements 10 in memorandum-books; and it has for its objects to provide a cheap and simple device for holding the covers of the book together, and to hold any number of pages together, so that any page may be turned to immediately after opening the book. These objects 15 I attain by the means illustrated in the accompanying drawings, in which—

Figure 1 represents a perspective view of a memorandum-book having my device attached 20 thereto. Fig. 2 represents a side elevation of the same, showing the elastic bands in section; and Fig. 3 represents a perspective view of my improved elastic band.

The letter A in the drawings indicates a 25 memorandum-book of the usual construction, having covers B and C, between which are secured the usual blank leaves. Secured to one of the covers is a loop, D, of suitable material, through which is passed the elastic split band 30 E, the inner part of the band E being for the purpose of holding a place in the book, so that it may be turned to immediately after open-

ing said book, and the outer part of the band being for the purpose of holding the covers or the book itself together, as shown plainly 35 in Fig. 1 of the drawings. The elastic band can be secured, however, in any desired manner.

The advantage of my device over the old way, where one band is used, is that when a 40 person has made an entry and wishes to keep the place, so that it can be turned to as soon as the book is opened, the inner part of the band E is inserted over the proper page, holding it to the cover, as shown in Figs. 1 and 2, 45 and when the book is closed the remaining portion of the band is extended around the outside of the covers and the book itself, holding the whole together.

Having thus fully described my invention, 50 what I claim, and desire to secure by Letters Patent, is—

1. The new article of manufacture herein described, consisting of an elastic band formed of one piece, split and adapted to serve the 55 purpose specified.

2. The combination of an elastic split band with a book, substantially as described.

In testimony whereof I affix my signature in presence of two witnesses.

EDWIN L. YEWELL.
